UNITED STATES PATENT OFFICE.

PETER HUFF, OF NEW YORK, N. Y.

PLATFORM-WAGON.

SPECIFICATION forming part of Letters Patent No. 287,541, dated October 30, 1883.

Application filed July 25, 1883. (No model.)

To all whom it may concern:

Be it known that I, PETER HUFF, of the city, county, and State of New York, have invented certain new and useful Improvements 55 in Platform-Wagons, of which the following is a specification.

This invention has reference to certain improvements in the construction of platform-wagons, whereby the load can be easily unloaded either at the end or side of the wagon; and the invention consists of a wagon the platform of which is hinged to the front bolster, and raised or lowered at the rear part by upright screw-posts, screw-nuts, and bevel-gears. 15 On the platform is supported a wagon-body, which may be made of one or more sections that are supported on roller-carriages, which are adapted to turn on their vertical axes into a position at right angles or parallel to the 20 longitudinal axis of the platform, so that the sections of the wagon-body may be moved over the end of the platform or over the sides. The platform itself consists of a skeleton frame with retaining side flanges and raised 25 circular guides at the intersection of the longitudinal and transverse rails of the platform. The roller-carriages of the body-sections turn around the raised guides when they are turned by means of lever-arms and connecting-rods. 30 applied to the upright shafts of the roller-carriages. The body-sections are secured by suitable locking devices to the platform and to each other, which will more fully appear hereinafter, and finally be pointed out in the claims.

35 In the accompanying drawings, Figure 1 represents a side elevation of my improved platform-wagon. Fig. 2 are details of the device for holding the body on the platform. Figs. 3 and 4 are end elevations of the wagon; Fig. 5, a bottom view of the wagon-body; Fig. 6, a detail plan of the platform; Fig. 7, a detail of one of the roller-carriages of the wagon-body, and Figs. 8 and 9 are side elevations of freight-cars constructed on the principles 45 embodied in my platform-wagon.

Similar letters of reference indicate corresponding parts.

A A in the drawings represent the body of my improved platform-wagon. This body is 50 made of one or of two or more separate sections, which are supported on roller-carriages B, that are applied by vertical yokes b to

grooved pivots b', strapped to the bottom of the body-sections A, as shown in Fig. 7. The roller-carriages B may thereby be turned around the pivot b' and set parallel to or at right angles to the longitudinal axis of the supporting-platform C, as required. Each roller-carriage B is constructed of two rollers that are applied at proper distance from each other. To 60 the axle b² is applied the upright yoke b, by which the connection with the fixed pivot b' is made, the flange or head of which retains the roller-carriage B on the wagon-body. In place of the construction shown, any other 65 construction by which the roller-carriage may be turned on its vertical axis may be used, as I do not confine myself to the construction shown. To the yoke b of each roller-carriage is rigidly applied a laterally-extending lever-arm, d. This lever-arm is pivoted to a slide-rod, d', that is guided on straps d² at the bottom of the body-sections A A, the ends of the slide-rods d' being connected by chains or ropes d³, that are passed over sprocket-wheels 75 or pulleys d⁴, as shown clearly in Fig. 5. One of the lever-arms d may be extended laterally, so as to project beyond the wagon-body, so that all the roller-carriages may be turned and set into proper position by moving the 80 lever-arm d in one or the opposite direction.

The platform C is constructed, in the nature of a skeleton platform, of two pairs of longitudinal rails, e e, and two pairs of transverse rails, e' e', for each section A. The longitudinal and transverse rails of the skeleton platform C are securely riveted together, and the outer edges of each pair of rails provided with bent-up flanges e², along which the roller-carriages are guided, and by which the body-sections A 90 A are prevented from moving off the platform. At the points of intersection of the longitudinal and transverse rails raised circular portions e³ are located, the diameter of which is equal to the distance between the 95 rollers of the roller-carriages B. The raised portions e³ serve for guiding the roller-carriages in their axial motion from a position at right angles to or parallel to the longitudinal axis of the platform, and also for steady-ing the body-sections on the skeleton plat-form.

The sections A A of the wagon-body are locked to each other and to the platform C by

means of spring-hooks D, which engage recessed plates or eyes of the wagon-body. By means of a transverse crank-shaft having eccentrics, the spring-hooks can be released from 5 the eyes of the wagon-body when the latter are to be moved off the platform. The sections A A of the wagon-body are further secured to the platform D by hooks f, which are keyed to a transverse rod, f', extending across the 10 platform C, and turning in bearings of the same. The hooks f are made to engage eyes or staples f² of the wagon-body by means of a laterally-movable lever, f³, that is pivoted to the lower part of the hook f, back of the rod 15 f', and which is retained on a fixed laterally-extending rest, f⁴, of the platform C. By releasing the lever f³ from the rest f⁴ the hooks f on the rod f' can be readily disengaged from the eyes f². The body-sections A A can then 20 be readily moved on the platform, the locking-hooks preventing the jumping of the body-sections from the platform.

The platform C is hinged at its front part to a bolster of the fifth-wheel C', and applied 25 at the rear part, by means of side staples, g, rollers g', and links g', to the ends of longitudinal leaf-springs E, which leaf-springs are centrally pivoted to vertically-adjustable screw-bolts E', that are raised or lowered by screw-nuts E², operated by a bevel-wheel transmission. (Shown in Figs. 1 and 4.) The shafts of said bevel-gear wheels turn in bearings of the hind axle and of the reach E³, and are set in motion by a crank-shaft in front of the 30 hind wheels, as shown in Fig. 1. The reach E³ extends from the hind axle to both sides of the front bolster, and is then bent downward to the front axle and connected by a transverse piece to the center pivot of the front axle, 35 so that the front wheels can turn independently of the reach. The middle part of the reach is inclined, so that when the hind part of the platform C is lowered it will assume the inclination of the middle part of the reach E³. 40 By thus lowering the rear part of the platform the body-sections A A can be readily transferred from the platform to any place where the load is to be deposited, for which purpose auxiliary rails are to be used, on 45 which the body-sections are rolled to the point of discharge. The fifth-wheel C is also supported on strong elliptic leaf-springs, the hounds of the wagon-shaft being applied, in the usual manner, to the fifth-wheel of the 50 wagon. When the load is to be discharged, the roller-carriages of the body-sections are first, by the mechanism described, set in the direction in which the same are to be moved. The locking devices of the body-sections are 55 then released, so that the sections are free to be moved on the platform. When the sections A are to be moved over the rear end of the platform in a longitudinal direction, the rear part of the platform is lowered to the required 60 extent, whereby the body-sections A can be moved readily over the rails of the platform and over the auxiliary rails to the place of dis-

charge, as before described. The body-sections A can also be removed laterally from the platform for which purpose the transverse 70 rails are not provided with end flanges. The roller-carriages are turned into a position parallel to the longitudinal axis of the platform and the locking devices of the body-sections A released. The forward body-section is then removed laterally, and the rear section moved forward, so as to take the place formerly occupied by the front section where its roller-carriages are turned, after which it is also moved laterally over the platform, and then 80 to the place of unloading.

The principle described may also be applied to the bodies of railway freight-cars, in which case either one or more sections may be used, which are also supported on axially-turning roller-carriages B B. The wagon-body A is either returned on the car-platform by means of hinged top and bottom side-boards h h and suitable locking devices, h', as shown in Fig. 8; or the sides of the car 90 may be provided with sliding doors, which leave sufficient space to permit the removal of the body-sections A A, as shown in Fig. 9. The cars are closed by transverse end walls, by which the movable sections are securely 95 held in position. Several body-sections may also be arranged sidewise of or above each other on supplemental platforms, as in Fig. 9, each section containing, preferably, a quantity sufficient to load a truck, whereby the 100 transfer of certain kinds of freight may be considerably facilitated.

Having thus described my invention, I claim as new and desire to secure by Letters Patent—

1. The combination, in a platform wagon or car, of a supporting-platform and a wagon-body, made of one or more sections and supported on axially-turning roller-carriages, so as to be adapted to be moved in longitudinal or lateral direction, substantially as set forth. 105

2. In a platform wagon or car, the combination of a supporting-platform constructed of pairs of longitudinal and transverse rails, a wagon-body composed of one or more sections supported on axially-turning roller-carriages, 115 and means whereby the said roller-carriages are set into a position transversely to or parallel to the longitudinal axis of the platform, substantially as set forth.

3. The combination of a supporting-platform, made of pairs of intersecting longitudinal and transverse rails, a wagon-body composed of one or more sections supported on axially-turning roller-carriages, means whereby the roller-carriages are set into a position 125 transversely to or parallel to the axis of the platform, and means whereby the sections of the wagon-body are locked to each other and to the platform, substantially as set forth.

4. The combination of a supporting-platform, C, constructed of pairs of longitudinal and transverse rails e e and e' e', the outer rails of which have flanges e², while the points of intersection of the pairs of rails are provided 130

with raised guide-disks e^3 , with one or more sections, A A, of the wagon-body supported on axially-turning roller-carriages, and provided with means for turning the roller-carriages in a position transverse to or parallel with the longitudinal axis of the platform, substantially as described.

5 5. In a platform-wagon, a skeleton platform constructed of intersecting longitudinal and transverse guide-rails, the outer rail of each pair being flanged, and the points of intersection of the longitudinal and transverse rails provided with raised guide-disks, arranged substantially as described.

10 6. In a platform-wagon, the combination of

a platform hinged to a bolster of the front axle, and provided with mechanism for raising or lowering the rear end, a wagon-body composed of one or more sections, which are supported on axially-turning roller-carriages, and means 20 for locking the sections to the platform and to each other, substantially as specified.

In testimony that I claim the foregoing as my invention I have signed my name in presence of two subscribing witnesses.

PETER HUFF.
